UNITED STATES PATENT OFFICE

112,691

DESIGN FOR AN INVALID WALKER UNIT

Adrian Comper, Pittsfield, Mass., assignor to Comper Manufacturing Company, a corporation of Massachusetts

Application June 16, 1938, Serial No. 77,890

Term of patent 7 years

To all whom it may concern:

Be it known that I, Adrian Comper, a subject of the King of England, residing at Pittsfield,
in the county of Berkshire and State of Massachusetts, have invented a new, original, and ornamental Design for an Invalid Walker Unit, of which the following is a specification, reference being had to the accompanying drawing, forming part thereof.

The figure is a perspective view of an invalid
walker unit showing my new design.

The dominant feature of the design resides in the parts shown in solid lines.

I claim:

The ornamental design for an invalid walker
unit, as shown and described.

ADRIAN COMPER.
